UNITED STATES PATENT OFFICE.

HUBERT R. HUMPHREY, OF KALAMAZOO, MICHIGAN.

DESIGN FOR A GAS HEATER.

60,245.

Specification for Design.

Patented Jan. 17, 1922.

Application filed June 30, 1921. Serial No. 481,663. Term of patent 14 years.

To all whom it may concern:

Be it known that I, HUBERT R. HUMPHREY, a citizen of the United States, residing at the city and county of Kalamazoo and the State of Michigan, have invented a new, original, and ornamental Design for a Gas Heater, of which the following is a specification, reference being had to the accompanying drawing, forming part thereof.

The figure is a front view of a gas heater, showing my new design, a portion of the radiants being indicated by full lines and the remainder indicated conventionally by dotted lines.

I claim:

The ornamental design for a gas heater, as shown.

HUBERT R. HUMPHREY.
